UNITED STATES PATENT OFFICE.

RUDOLPH A. HOLMES, OF DETROIT, MICHIGAN, ASSIGNOR TO MORGAN & WRIGHT,
A CORPORATION OF MICHIGAN.

STITCHER MECHANISM FOR TIRE-MAKING MACHINES.

Application filed September 22, 1920. Serial No. 412,001.

To all whom it may concern:

Be it known that I, RUDOLPH A. HOLMES, a citizen of the United States, residing at Detroit, county of Wayne, and State of Michigan, have invented certain new and useful Improvements in Stitcher Mechanisms for Tire-Making Machines, of which the following is a full, clear, and exact description.

10 This invention relates to stitcher mechanisms for tire-making machines and more particularly to a stitcher mechanism including oppositely disposed rotatable stitchers contacting with the entire fabric surface 15 and laying fabric from the crown to the edge of the core and over the bead when the casing is of the bead type, being a continuation of my prior application Serial No. 136,618, filed December 13, 1916, as to all 20 matter common to the two applications.

One of the objects of the invention is to provide a simple and efficient apparatus of the kind described, which, when employed in the manufacture of tires provided with 25 beads, shall be adapted to accomplish the whole of the stitching operation without resorting to supplementary hand-stitching. Another object of the invention is to provide 30 a device in which tendency of the fabric to pucker in the stitching operation shall be obviated. Another object of the invention is to provide a device which shall cause uniform adherence of the fabric layers to one another in spite of various irregularities in 35 the fabric due to joints between successive strips, etc. And a further object of the invention is to provide the stitchers with supporting construction which permits of a reduction in their diameter and which also 40 permits of their initial adjustment for simultaneous contacting engagement with the fabric of the core as well as symmetrical operation on opposite sides of the core while the fabric is being laid.

45 In the accompanying drawings wherein one of the various possible embodiments of the invention is shown;

Fig. 1 represents a partial sectional plan view of apparatus showing the stitchers traversing a partially completed tire surface;

Fig. 2 indicates the position of the right hand stitcher on initial engagement with the core;

50 Figs. 3, 4 and 5 are similar views of suc-

cessive stages of operation following that shown in Fig. 2;

Fig. 6 is a detail view of one of the stitchers and the mountings thereof;

Fig. 7 is a sectional detail view taken on 60 the line 7—7, Fig. 6;

Fig. 8 is a side view of the stitcher shown in Fig. 6;

Figs. 9 and 10 are detail views of the yielding or sectional plunger arms used in 65 connection with the pneumatic mechanism for operating the stitchers, and

Fig. 11 is a vertical sectional detail showing a stop pin and its controlling mechanism.

Referring now to the drawings, 1 indicates a reciprocable support or carriage upon which mechanism including the stitcher-members and the operating means therefor is mounted. The stitcher mechanism comprises a pair of oppositely disposed stitcher-rollers 2 and 3, each of which with its applying mechanism, supports, etc., is identical, and a description of one will serve for both.

Each stitcher-member comprises, as shown more clearly in Figs. 6, 7 and 8 a pair of rollers 4 and 5. The part 5 is adapted to direct fabric toward the core surface or the surface of previously applied fabric and into the path of the stitching edge 6 of the roller 4. The periphery of the roller 4 is provided with a shallow groove 7 generally corresponding in shape to a tire bead.

These rollers are rotatably mounted upon a pin 8, supported by a rod 9, which is angularly as well as endwise adjustably mounted in the transversely apertured end of a stud 10 seated in a socket 11 on one end of and forming part of an angular-form carrier 12, a bolt 11' being provided to draw the stud into the socket 11 and thereby bind the rod 9 against the flanking walls of the socket. The carrier 12 is fulcrumed at 13 to a lever 14, and a spring 13' urges the carrier about its fulcrum in such wise as to move the stitchers toward each other and against the core. Preferably the stitchers are arranged to exert a slight skiving action on the fabric as it is laid, and to this end the pin 8 on which the stitchers revolve, is adjusted out of parallelism with the axis of the stud 10 and inclined slightly to the plane determined by the axes of rod 9 and stud 10.

Consequently when the stitchers 110

are revolved by traction against the core, they exert a skiving action which is uniform and constant for any given adjustment during the laying on of a ply of fabric. The more the axis of pin 8 is tilted from the right angular relation with respect to the axis of fulcrum 13, the greater the skiving action, and vice versa. Stud 10 is preferably positioned so that the plane formed by its axis and that of rod 9 is perpendicular to the axis of the fulcrum 13. Maximum clearance for the stitchers when they enter the undercut portion of the carcass immediately adjacent the beads is provided by the offset construction thus described above and relatively small stitchers may be used, thereby permitting wrinkles to be taken out of the fabric at and adjacent the beads where trouble has heretofore been encountered.

Endwise adjustment of rod 9 permits the stitchers to be set to simultaneously contact with the fabric on the core at the beginning of a laying on operation. The angular-form-carrier 12 is provided with a projecting heel piece 12' and a rubber or other resilient cushion 15, positioned between it and a similar projecting piece on the lever 14, is adapted to cushion the blow of the stitchers when their supporting and actuating mechanism is straightened out as shown in Fig. 1 preliminary to their initial contact with the core, as well as to permit the operator to momentarily apply pressure to the stitchers when desired.

To the other extremity of lever 14 is pivotally attached a section 16 (see Figs. 9 and 10) of a plunger, the other section 17 of which is pivotally attached to a piston head 18 mounted to reciprocate in a chamber 19. The section 17 of the plunger is provided with a socket into which a reduced portion of the section 16 fits and is connected thereto by means of a pin 20 operating in a slot 21. The two sections are yieldingly held apart by a coiled spring 22 surrounding them both and lying between the extremity of the lever 14 and the point of pivotal connection of the section 17 with the piston head 18. The lever 14 is pivoted to the carriage at 23 and swings thereabout in accordance with changes in the curvature of the core or partially completed tiré surface.

Lever 14 is moved about its fulcrum 23 by admitting air under pressure to the cylinder 19 and the stitchers are thereby held elastically against the core. Springs 22 encircling the telescoping sections of the extensible link 17, cushion the blow where the air is first admitted to the cylinder 19 and as these compressed springs work in the same direction as the air they have a sort of supplemental action which is especially advantageous when the stitchers cross a

spliced point permitting the stitchers to quickly and immediately take care of the irregularity presented thereby.

Mounted on lever 14 and swinging therewith is a chamber 25, to which, as well as to chamber 19, air is adapted to be supplied through flexible conduits, 24-24'. Mounted in chamber 25 is a piston head whose plunger 25' is loosely pinned as indicated at 26 to a link 27 whose forked end is loosely articulated to the lateral pins 28 of the carrier member 12. According to this construction at certain times each stitcher is adapted to swing upon its fulcrum connection 13 with the lever 14, this motion being under control of the air chamber 25 which acts against and overcomes the spring 13'.

Projecting from the wall of chamber 19, and situated between chambers 25-25 is a single chamber 29 in which is a plunger 29' operable at certain times upon projecting arms 30 integral with levers 14. This chamber is supplied with air through a flexible conduit 31.

When the carriage is first moved forward the stitchers must not be too close to the central plane of the rotating core or else they will materially resist their own further advance. On the other hand, in stitching under the beads the stitchers must approach closer to the central plane of the core than when they initially engage the core at the tread. To limit the turning movement of lever 14, about its fulcrum 23 at the outset of a laying on operation, a stop in the form of a plunger 32, Fig. 11, is slidably mounted in the carriage 1 with its upper end normally projected a short distance above the top of the carriage 1 by a spring 33, which is connected to a bell-crank lever 34 fulcrumed at 35 to the carriage and loosely pinned at 36 to the lower end of the plunger 32. The opposite free end of the lever 34 is provided with a roller 37 which is adapted to ride up the inclined surface 38 of the stationary base 39 on which the carriage 1 reciprocates. The stop or plunger 32 limits outward movement of the rear end of lever 14 at the outset of a laying on operation. After the forward movement of the carriage 1 has carried the stitchers into engagement with the core or fabric being laid thereon, so that there is no further possibility of the forward end of the lever moving too close together, the stop or plunger 32 is withdrawn and held in the solid line position shown in Fig. 11 by the cam action of the surface 38 on the bell-crank lever 34. And therefore when the stitchers arrive at the bead portion of the casing or carcass the levers 14 are free to move inward the required distance to smooth the fabric on the under or lower surface of the beads as illustrated in Fig. 5.

The carriage 1 and parts heretofore men-

tioned associated therewith are adapted to be reciprocated toward and away from a rotatable core 40 intermediate the stitchers 2 and 3. Any suitable means may be employed to actuate the traveling carriage 1, the general type thereof well known to those skilled in the art and similar to that disclosed in U. S. patent to Harsel, 1,279,337, September 17, 1918. The specific mechanism for actuating the carriage not forming a part of the present invention requires no further description.

The fabric is first laid on the core member 40 and the core rotated at a relatively high speed. The carriage with the stitchers 2-3 and their actuating mechanism, is then moved forward and the normally spread apart spring pressed latches 41 are brought toward each other manually to free the pistons in the cylinders 25. During the advance of the carriage toward the core, air under pressure is admitted to cylinders 25 and thereby the linkage mechanism supporting the stitchers is caused to assume a stretched out condition as shown in Fig. 1 of the drawings. In this movement of the linkages the springs 13' coiled about the fulcrums 13 are overcome and the resilient cushions 15 absorb the shock of the heel pieces 12' against the opposed heel piece or abutment 42 of the lever 14. Then compressed air is admitted to the cylinder 19 and the levers 14 are swung about their fulcrums 23 so as to carry the stitchers toward one another, but the stop 32 being now above the surface of the carriage 1, limits their approach toward one another. The parts are now in the position shown in Fig. 2 and ready to engage the tread surface of the core, which they do in the further forward movement of the carriage. As the carriage continues to move forward the stretching rollers smooth the fabric onto the core or the previously laid ply and during this operation the stitchers are held against the core largely by the elastic pressure of compressed air in cylinders 19 acting on the pistons 18. About the time the stitchers reach the widest part of the core in their forward movement and with the parts in nearly the same position as illustrated in Fig. 1, air pressure in the cylinder 25 is relieved. This does not noticeably alter the position of the parts, which remain unchanged and stretched out or distended excepting as they swing about pivot 23 to conform to the outline of the core. If the casing being made has no beads the carriage continues its movement, the stitchers moving inward until the fabric is laid completely on each side of the casing when the movement of the carriage is halted and simultaneously air is shut off from the cylinder 19. The stitcher parts are then free to rotate about the fulcrum 13 under the action of the spring 13' coiled

around the same and when, at the same time, air is admitted to the cylinder 29 to thrust its portion 29" against the lugs 30 integral with lever 14 the stitchers are separated and thrown clear of the core. In the movement of the stitcher carriers 12 about the fulcrums 13 under the action of springs 13' to the doubled up condition illustrated in Fig. 4 latches 41 engage under pins 26 and hold the linkage doubled.

If the casing being made is of the bead type the operation is the same until the stitches encounter the bead, which of course, is after the pressure on cylinder 25 is relieved. On reaching the bead the stitchers are free to turn from their stretching out position illustrated in Figs. 1 and 2 to the doubled up position illustrated in Fig. 4 and in this movement they are assisted by the spring 13' coiled about the fulcrum 13. And as will be obvious from what has been said before, when the stitching linkages are in a doubled up condition latches 41 engage under pins 26 and hold the linkage doubled. The carriage, of course, travels further in stitching over beaded than straight-sided-casings. In either of the two cases mentioned, at the end of a stitching operation with the stitchers in a doubled up position and held clear of the core, by reason of the spreading action of the plunger 29' on the lateral arms 30 of the levers 14, the carriage 1 is retracted to a position which allows the core to be removed and another substituted. The successive stages of operation are illustrated in Figs. 2, 1, 3, 4, and 5 in the order enumerated when a beaded casing is being formed.

It is to be noticed that in applying the fabric around the sides of the core that the stitchers fulcrum about their pivots 13, but when the bead is reached their peripheral grooves 7 embrace it and thereafter the stitchers swing about grooves 7 as a center. The curve of the groove 7 conforms substantially to the curve of the bead. In laying the fabric on the bottom side of the beads the stitchers assume the position illustrated in Fig. 5.

The stitcher mechanism described is simple and efficient and by virtue of the shape of the stitcher members and their conformity to the fabric placed over the bead the whole of the stitching operation may be accomplished without resorting to supplementary hand-stitching. The adjustability of the stitchers into a position oblique to the core affords a desired downward sweeping and skiving action on the fabric and consequently prevents puckering thereof during the application. The combination of springs 22 and the sectional plungers provides a more uniform adherence of the fabric layers to one another in spite of irregularities in the fabric which may occur due to joints be-

tween successive strips, etc., than where dependence is placed alone upon coiled springs to rotate the stitchers about their pivotal points.

5. The rubber cushion 15 permits a slight relative movement between the parts 2 and 3 and the pneumatic actuating mechanism to take up slight irregularities in the surface of the fabric.

10. Obviously the stitchers 2 and 3 could be made in one piece and likewise the plungers or links 16-17 could be made integral when the refinement their use affords is not demanded by the work.

15. From Figs. 6 and 7 it will be clear that the socket 11 on one end of, and forming part of, the angular-form-carrier 12, is bored out circular and hence permits of rotating or adjusting the stud 10 therein. This construction permits not only adjusting the stitchers to get a desirable amount of skiving action, but also locating their points of contact with the core at directly opposite points and on the exact horizontal central line of the core 25 if desired.

And as many other apparent and widely different embodiments of this invention may be made without departing from the spirit thereof, it is to be understood that I do not intend to limit myself to the specific form of the invention as set forth except as indicated in the appended claims to which reference should be made for an understanding of the scope of the invention.

35. Having thus described my invention, what I claim and desire to protect by Letters Patent is:

1. In a machine for laying fabric on a core, in combination, a rotatable stitcher 40 having spaced peripheral flanges and provided with a shallow groove intermediate said flanges, said groove being shaped to conform fabric to a bead, and means for moving said stitcher transversely over the 45 surface of a partially completed tire into contact with the fabric over the bead.

2. In a mechanism for laying fabric on a core, in combination, a swinging roller member having a shallow concave channel 50 flanked by flanges shaped to conform to the surface of fabric over the bead, and a device for moving said roller member into contact with and transversely of fabric on said bead and permitting said member to swing 55 while moving transversely in contact with fabric on the core so that its surface conforms said fabric to the bead.

3. In a mechanism for laying fabric on a core, in combination, a roller having a surface shaped to conform to the surface of fabric on a bead, a roller for sweeping the fabric into the path of said first mentioned roller and a device for moving the rollers into contact with that portion of fabric 65 at the tread and that portion about the bead.

4. In a mechanism for laying fabric on a core, in combination, a roller having a surface shaped to conform to the surface of fabric on a bead, a roller having a rounded surface adapted to sweep fabric into the path of 70 the first mentioned roller and a device for moving the rollers radially across the core and into contact with the fabric at the tread and over the bead.

5. In a mechanism for laying fabric on a core, in combination, a pair of rollers mounted on a common shaft, one of the rollers having a grooved periphery, the groove conforming to the shape of fabric over the bead, the other roller also contacting with the bead and having a rounded surface for directing the fabric into the path of the first mentioned roller and a device for moving the rollers into contact with fabric at the tread and over the bead. 85

6. In a mechanism for laying fabric on a core, in combination, a rotatable fabric applying member, a device for moving said member from the crown of fabric applied to the core towards the edges thereof while 90 maintaining said member in contact with said fabric and means to adjust said member about an axis substantially perpendicular to the core adjacent the stitching point for rotation only in oblique relation to the 95 plane in which lies the axis of the core and the point of contact of said rotatable fabric applying member with fabric on the core.

7. In a mechanism for laying fabric on a core, in combination, a pair of rotatable 100 fabric applying rollers, a device for moving said rollers transversely of the core, and means to adjust said rollers to exert a substantially uniform skiving action on the fabric during a laying on operation. 105

8. In a mechanism for laying fabric on a core, in combination, a pair of rotatable fabric applying rolls, arms for supporting said rolls, a device for moving said arms and said rolls transversely of the core, and mechanism on said arms for adjusting said rolls obliquely with respect to the plane of their movement transversely of the core, and about axes which are adjacent and parallel to the planes of their respective 110 stitching peripheries. 115

9. In a mechanism for laying fabric on a core, in combination, a pair of rotatable fabric applying rolls, pivotally held arms for supporting said rolls, a device for moving said arms and said rolls transversely of the core and swivel members on said arms for adjusting said rolls obliquely with respect to the plane of their movement transversely of the core. 120

10. In a mechanism for laying fabric on a core, in combination, rotatable fabric applying rolls, arms for supporting said rolls, lever members moving said arms toward and away from the core, a pneumatic 130

- mechanism controlling the action of said lever members and springs cooperating with said lever members to move said rolls.
11. In a mechanism for laying fabric on a core, in combination, oppositely disposed fabric applying rotatable rolls, arms for supporting said rolls, lever members for moving said arms toward and away from one another and the core, pneumatically operated plungers connected with said levers, each of said plungers having a stem comprising relatively moving sections and a spring controlling the movement of said sections.
12. In a mechanism for laying fabric on a core, in combination, a pair of oppositely disposed fabric applying rotatable rolls, pneumatic means for urging said rotatable members toward and from said core and a rubber cushion for permitting slight relative movement between said rolls and said pneumatic means along the path of motion provided by said pneumatic means.
13. In a machine for laying fabric on a core, in combination, opposed rotatable stitchers, a lever fixedly supporting each stitcher, means for operating said lever including an actuating fulcrum and an actuating pivot spaced from the fulcrum, and an adjustable connection between each stitcher and its lever located at one side of a line through an axis of its fulcrum and pivot.
14. In a machine for laying fabric on a core, in combination, opposed stitchers, means for rotatably supporting each of said stitchers including a lengthwise adjustable post in substantial parallelism and contiguous the plane of the stitchers' effective periphery, and articulated mechanism for actuating the posts to move the stitchers transversely of the core.
15. In a machine for laying fabric on a core, in combination, opposed stitchers, means for rotatably supporting each of said stitchers including an axially arranged pin, an angularly adjustable post supporting the pin and arranged at substantially right angles thereto and in substantial parallelism and contiguous the plane of the stitchers' effective periphery, and mechanism connected to each post at one side of the axis of rotation of each stitcher for operation thereof.
16. In a machine for laying fabric on a core, in combination, opposed stitchers grooved to conform fabric to the bead, means for rotatably supporting each of said stitchers including a post in substantial parallelism and contiguous the plane of the stitchers' effective periphery, and articulated mechanism for actuating the posts to move the stitchers transversely of the core.
17. In a machine for laying fabric on a core, in combination, opposed stitchers grooved to conform fabric to the bead, means for rotatably supporting each of said stitchers including an axially arranged pin, a post supporting the pin and arranged at substantially right angles thereto and in substantial parallelism and contiguous the plane of the stitchers' effective periphery, and a mechanism connected to each post at one side of the axis of rotation of each stitcher for operation thereof.

Signed at Detroit, Michigan, this sixteenth day of September, 1920.

RUDOLPH A. HOLMES.
